UNITED STATES PATENT OFFICE.

WILLIAM L. SAUNDERS, OF NEW YORK, N. Y., ASSIGNOR TO THE INGERSOLL
ROCK DRILL COMPANY, OF SAME PLACE.

COMBINED DRILLING, CHANNELING AND GADDING MACHINE.

SPECIFICATION forming part of Letters Patent No. 394,212, dated December 11, 1888.

Application filed June 9, 1887. Serial No. 240,816. (No model.)

To all whom it may concern:

Be it known that I, WILLIAM L. SAUNDERS, a citizen of the United States, residing at New York, in the county of New York, State of New York, have invented certain new and useful Improvements in a Combined Drilling, Channeling, and Gadding Machine, of which the following is a description.

My invention consists in an improved machine for sinking round holes and cutting longitudinal channels in stone, it being adapted to perform both the processes known in the art of stone-quarrying as "channeling" and "gadding," the same organization being adapted for use as a gadder capable of operating in any position, and with slight modification and the substitution of a gang of drills for a single drill-steel it becomes a channeling-machine—that is, one capable of cutting a continuous open channel, also, in any desired position.

My improved machine comprises a reciprocating direct-acting percussion rock-drill mounted in a shell-piece, within which it is vertically adjusted by means of a feed-screw in the ordinary manner. The shell is carried upon a pair of horizontal supports, preferably tubular, which supports are centrally pivoted upon a rod, bar, or continuous screw, which forms the axis of the drilling apparatus, the tubular supports and engine being radially adjustable thereupon and adapted to be supported at any angle, from the horizontal to the vertical, the axial support being also formed with a continuous screw-thread, which, being connected by suitable gearing with the carriage carrying the drilling-engine, affords means by which the engine is moved laterally in either direction along its supports when making an open cut or channel. The extremities of the axes upon which the tubular supports are mounted pass through end pieces which carry extensible sleeved arms, within which latter are adjustably secured the legs upon which the machine as a whole is supported, and the legs themselves are each provided at its extremity with a caster-wheel, upon which the machine is supported when not in operation, in order to facilitate its travel from place to place; but when in operation by a simple contrivance

the caster-wheels are removed from the floor and rendered inoperative, and the machine supported upon the ends of the legs themselves, or upon leg-pins, so as to have a solid 55 and firm bearing upon the floor of the quarry.

According to the prior state of the art two operations have been necessary to channel out a block of stone, a gadder being employed to put in a row of horizontal holes at the bottom of the bench, and a channeling-machine being used to cut an open channel from above, the mass of stone inclosed between the channel and the row of holes being broken out by wedges. Various other forms of apparatus have been used for this purpose, including percussion-drills, with which a series of non-communicating round holes were bored, the partitions between said holes being broken down by a brooch, thus forming 60 a channel. Rotating diamond drills were also used for the same purpose, also the channeling-machines of the kind previously referred to. Up to the present time no other machine has been produced or method devised 65 by which both operations are satisfactorily carried out.

The details of construction, arrangement, and operation of the various parts and elements of my apparatus will be hereinafter 70 fully described, reference being had to the accompanying drawings, in which—

Figure 1 is an elevation, partly in section, showing my combined channeling and gadding machine in position as a channeler, but 75 with the machine raised and the caster-wheels down, in position to be moved in the direction of the work. Fig. 2 is an end view of the supports and lateral feeding mechanism, the relative position of the shell and engine being indicated in dotted lines. Fig. 3 is an end view, partly in section, looking in the direction of the arrow, the engine and shell being removed. Figs. 4 and 5 are detail views of the pawl-head, showing the means for throwing the 80 pawls out of action to stop the rotation of the drill-rod and piston when the machine is used 85 as a channeler. Figs. 6, 7, and 8 are detail views of the preferred form of caster-wheel and supporting-leg. Fig. 9 is a side elevation of 90 the machine in position to operate as a gadder. Fig. 10 is a detail view showing a portion of 95 100

the piston-rod, the chuck, and a drill-steel in position. Fig. 11 is a section through the shell and chuck on the line 11 11 of Fig. 1. Fig. 12 is an elevation of the drill-clamp, showing the drills in position. Fig. 13 is a drill, showing the cross-head upon which the clamp and drills are secured, together with a section of the chuck and portion of the piston-rod, showing the dowel extending from said cross-head thereinto. Fig. 14 is an enlarged detail showing a modified form of easter-wheel with portion of leg in position.

Similar letters denote like parts throughout.

The drilling-engine A, which is a percussion rock-drill, steam or air driven, is mounted upon a shell, B, which latter is formed with grooves or ways b, within which the drilling-engine is held and guided when moved by its feed-screw a, and in the lower portion of which also move wings C of the cross-head C', to which the drill-clamp D is secured by bolts d, the said shell B being almost flat in form, so as to occupy as little place as possible, and being also extended downward a sufficient distance to hold and guide the cross-head at the lowest possible position throughout its entire stroke; but I sometimes construct the shell of less length, using a detachable extension secured to its lower portion, and upon which the drill-clamp is guided and supported. The piston-rod a' terminates in a chuck, E, within which the inner end of the drill-steel E', or the shank or dowel F, secured to the cross-head C', may be interchangeably secured by means of bolts e. The dowel F is of the same size as the inner ends of the drill-steel, and is a piece of steel or iron of smaller cross-section or weaker than the piston-rod, so that instead of the entire strain and risk of breakage being upon the piston-rod, as would be the case were the cross-section secured directly thereto, the dowel, being weaker, will give way soonest and be bent or broken, thus preventing injury to the piston-rod, while the dowel itself, being usually only secured to the cross-head by a set screw or pin, f, can readily and quickly be replaced at any time.

The drill-clamp D is a piece of metal substantially oblong in form and large enough to contain a recess for the reception of the desired number of drills, (in the present instance three,) the drills being let in said recess with their ends abutting its top side, in which position they are secured by a set-screw, d'. In the ordinary course of wear the drills G will become of uneven length; but by the insertion of a small strip of metal at the end or ends of the shorter ones their inequalities of length will be overcome. The drill-receiving recess in the clamp D may be slightly deeper than the thickness of the drills, and the face of the cross-head C' is formed with a slight projection, g, registering with said recess. When the clamp is in position, its flat top side, e', will fit under and abut the under-cut portion f' of the cross-head, the projection g projecting into the recess and against the

body of the drills G, in which position the parts are firmly secured together by clamp-bolts d, which fit into the coinciding recess H, formed in both clamp and cross-head.

The pawl-head h of the drilling-engine contains the rifle-bar or other device, by means of which and the ratchet I and pawls i rotary movement is imparted to the piston and drill-steel E' at each reciprocation thereof when drilling round holes. This movement cannot continue when the machine is operated as a channeeler, and under those conditions the pawls i are held away from the ratchet by means of screw stop-bolts i', which extend through the pawl-head from its exterior, and can by a few turns of the wrench be driven in or out to withhold or release the pawls I, according to the work required of the machine. Springs J and bolts j are provided, the inner extremities of said springs bearing against the pawls I, but holding them in operative position when released by the stop-bolts i'.

The frame upon which my improved machine is supported and carried consists of two end pieces, K, each of which is provided with upper and lower parallel tubular bearings, k, within which move horizontal arms L, formed with or provided at their outer ends with tubular leg bearings or supports l, within which are adjustably secured the legs M, upon which the apparatus is carried, the legs themselves being vertically adjustable in their supports l, and the arms L, to which said supports are attached, being horizontally and radially adjustable in their bearings k, (the latter feature being indicated in dotted lines in Fig. 1,) thus rendering the legs universally adjustable.

The leg bearings or supports l are shown as rigidly attached to the arms L, and at such an angle as will slightly spread their lower extremities. It will be obvious, however, that this angle can be made greater or less according to circumstances, and, if desired, the arm L and supports l may be adjustably connected. Between the end pieces, K, is supported a frame, consisting of a pair of tubular guides, N N, which are preferably plain metallic tubes, although they may be solid brass, attached in equidistant positions from the center of yokes or heads n n', formed or provided with hollow cylindrical projections O, upon which the tubes are firmly fitted, and to which the heads are rigidly attached by means of longitudinal bolts m, passing through both heads, projections, and tubes, and uniting them into a strong and rigid frame, the tubes N being firmly held at their extremities both by longitudinal pressure and the internal support of the projections O upon the heads n n'.

The frame N N is pivotally attached to the end pieces, K, and at the same time supported thereon by means of a strong central longitudinal bar, J', which passes through the axes of the yokes n n' and through the centers of the end pieces, K, its extremity or extremities be-

ing screw-threaded and provided with jam-nuts $j' j^2$, by loosening which the frame, together with the drilling-engine, can then be turned into any desired position, the extremes being indicated in Figs. 1 and 9, and when in the desired position, by setting said jam-nuts the heads $n n'$ will be firmly held between the end pieces, K, and further rotation of the frame N N will be effectually prevented. The nuts $n n'$ may, however, be separately provided with axial-supports, in which case the feed-screw J' need not project therethrough, being merely secured thereto.

The axial bar J' is provided with a screw-thread extending the entire distance between the heads $n n'$, which screw-thread carries an internally-screw-threaded gear-wheel, P, in mesh with a gear-pinion, p, from the axis of which extends a hand-lever, P'. Upon the tubular supports N is mounted a laterally moving or sliding carriage, Q, to the outer side of which the shell of the drilling-engine, (indicated in dotted lines in Fig. 2,) is secured by means of one or more suitable bolts, q, extending therefrom. The carriage Q is formed with split bearings R R', adjustable for wear, and it is further formed with an arm, q', supporting the axis of the beveled pinion p. The split bearings being adjustable, all undesirable lateral motion can be readily eliminated, and in order to secure the drill in its desired position, instead of two pairs of bolts, the lower bearing, R', is provided with an extended hand-screw, r, by means of which the bearing R' can be firmly clamped upon its support, and all looseness, rattling, jarring, or vibration entirely prevented.

The lower extremities of the legs M are bifurcated, as shown in Figs. 6 and 7, and provided with caster-wheels S, which wheels are formed with or rigidly secured to their axles s, which are then placed in position in recesses T in the bifurcations referred to, where they are held in position by transverse bolts t. Said axles are also drilled from one extremity to their centers, internally screw-threaded, and each provided with a set-screw, U, and the caster-wheels themselves are drilled through to form one or more sets of holes, u, all of them intersecting the axis and adapted to receive the leg-pins V, which are inserted when the machine is in operative position. By placing a bar under projecting axis s the leg may be easily raised from the ground and said foot-pin passed through one or other of the sets of apertures in the caster-wheel, and when in position is firmly secured by means of the collar T' and set-screw U, thus readily and quickly converting the rotating into a solid support for the machine. As shown in Fig. 14, this arrangement may be modified by forming the leg-pins directly upon the lower extremity of the legs themselves, in which case the bifurcated caster-support is a separately-formed casting, v, upon which the leg is held in position by means of an adjustable collar,

W, or wedge W', and the separate leg-pins are dispensed with.

In Fig. 9 the machine is shown with the frame and engine turned to a horizontal position, where it may be used for gadding or for cutting a horizontal channel. In this figure the machine is shown as standing upon its own feet—that is, resting upon the pointed extremities of the leg-bars M—this being a proposed modification, the caster-wheels, similar to those shown in Fig. 14, having been temporarily removed in order to lower the engine as much as possible. In practice, however, the casters will always be in position, the leg-pins being projected therethrough to a greater or less extent when the machine is in operation, in order to afford a solid and non-rotating support for the drilling apparatus.

In operation when it is desired to drill what are known as "round holes," whether horizontal, vertical, or at any intermediate angle, the machine is brought to position, traveling upon its caster-wheels, and on arriving the ends are raised and the leg-pins inserted through the caster-wheels projecting to a greater or less extent, according to the inequalities of the ground, when they are fixed in position and afford a firm and level bearing. The engine is then provided with an ordinary drill-steel, which is clamped in the chuck, and round holes are drilled, the engine being moved along its tubular supports in the desired direction, after the completion of each hole, by means of the hand-crank P'. When it is desired to use the machine as a channelear, it is brought to position as described, and a round hole is put down at each end of the cut, which, under ordinary circumstances, would be the length between the heads $n n'$, a distance of, say, ten feet. After the end holes have been drilled in position to form the beginning and end of the desired cut, or one hole has been put down at the desired distance from the termination at the last cut, or from the end of the bench, the drill-steel E is removed and the cross-head C' and gang of drills G substituted therefor, when by operating the hand-lever P', and continuously moving the engine so equipped back and forth along and above the space between the perpendicular terminals of the proposed channel, an open cut or channel is made, starting from the end hole, or from the termination of the previous cut, and gradually covering the entire distance, the gang of drills operating at right angles with their support, precisely as when the round holes were put in, except that the bottom pawls are thrown out of action by means of the stop-bolts i'. In the cutting of a channel the cut is made as long as the distance between the perpendicular extremities, the engine and drills being fed downward at each end of the cut, and then by moving the hand-lever P' fast or slow, and according to the nature of the material being operated upon, each horizontal cut is sunk to the de-

sired depth and the operation continued until a completed channel is formed, having perpendicular boundaries and not slanting away from its apparent extremities, as is the case in 5 all other channeling-machines, except when a separate cut is made for the purpose of straightening the ends of the channel, which must be done with the cutting-tools at an angle from the perpendicular.

10 It will be obvious that various other changes and modifications may be made without departing from the scope or nature of my invention, and therefore, although having described the same with particularity, I do not confine 15 myself to the precise details shown and described.

Having described my invention, what I claim, and desire to secure by Letters Patent, is—

- 20 1. The combination, with the engine-supporting frame, of a carriage on said frame, a drilling-engine secured upon said carriage, an axial feed-screw upon which said carriage is pivoted, an internally-screw-threaded gear-wheel mounted upon said feed-screw and secured to the carriage, and a beveled gear-pinion, also mounted upon said carriage and engaging the gear-wheel and having a hand-crank extending therefrom, substantially as 30 described.
2. The combination of a pair of parallel tubes or bars, end pieces supporting and uniting said bars, a direct-acting percussion rock-drilling engine mounted upon said supports, 35 a feed-screw passing through the axes of the end pieces, to which said supports are secured, and end pieces within which said feed-screw is immovably secured, substantially as described.

- 40 3. The combination, with suitable end supports, of the engine-supporting frame consisting of tubes N, heads n n', provided with projections fitting into the said tubes, and the bolts passing therethrough, substantially as 45 described.

4. The combination, with a frame adapted to carry a drilling-engine, of end supports formed with tubular bearings, laterally-extensible arms in said bearings, the extremities 50 of said arms being formed into leg bearings or supports, and supporting-legs arranged to be adjustably secured therein, substantially as described.

5. The combination, with an engine-carrying frame, of end bearings to which said frame is pivotally connected, tubular supports attached to said end bearings, and laterally-extensible leg-supports fitting therein, substantially as described.

- 60 6. In a drill-carrying frame, caster-wheels attached to each leg thereof, said wheels be-

ing formed with a radial perforation, and a leg-pin arranged to fit into and project through said perforation to support the drill-frame, substantially as described.

65 7. In an engine-carrying frame, legs therefor formed with bifurcations at their lower extremities, a supporting-wheel for each leg, said wheels being provided with axial perforations and having set-screws passing longitudinally through or into the axles thereof, and leg-pins arranged to pass through the said wheels, and to be secured in any desired position by the said set-screws, substantially as described.

75 8. In a drilling-engine frame, the combination, with a supporting-leg having bifurcated lower extremity, of a supporting-wheel therefor formed with axial perforations extending therethrough, means for securing said axle in the bifurcated extremity of the supporting-leg, a leg-pin arranged to be inserted in the aperture extending through the wheel, and a set-screw for securing the inserted pin in position, substantially as described.

85 9. In a drilling-engine, the combination of a shell having internal guideways and extended downwardly below the travel or feed of the engine, a cross-head drill-clamp having faces traveling in said guideways, and a removable dowel or shank extending between the piston-rod and cross-head, substantially as described.

90 10. In a drilling-engine, the combination of a supporting-shell having guides for the engine, and a cross-head having faces moving in the guide ways and secured to the engine by a removable dowel or shank, substantially as described.

100 11. In a drilling-engine, the combination of a supporting-shell having guides for the engine and cross-head, a cross-head having faces moving in the guideways and secured to the piston by removable dowel or shank, and a drill-clamp arranged to be secured to 105 and form part of the cross-head, substantially as described.

110 12. In a drilling-engine, the combination, with a shell extending below the feed of the engine, of a cross-head drill-clamp supported and guided in said extended portion of the shell, and connections between the cross-head and piston-rod, consisting of a dowel or shank of less strength than the piston-rod, substantially as described.

115 In testimony whereof I hereto affix my signature in presence of two witnesses.

WILLIAM L. SAUNDERS.
